(57) **CLAIM**

We claim the ornamental design for a vent, as shown and described.

DESCRIPTION

FIG. 1 is a perspective view of a vent according to the present invention and illustrating one position of a cover.

FIG. 2 is a front view of the vent shown in FIG. 1.

FIG. 3 is a rear view of the vent shown in FIG. 1.

FIG. 4 is a right side view of the vent shown in FIG. 1.

FIG. 5 is a left side view of the vent shown in FIG. 1.

FIG. 6 is a top view of the vent shown in FIG. 1.

FIG. 7 is a bottom view of the vent shown in FIG. 1.

FIG. 8 is a perspective view of a vent according to the present invention and illustrating an alternate position of the cover.

FIG. 9 is a front view of the vent shown in FIG. 8.

FIG. 10 is a rear view of the vent shown in FIG. 8.

FIG. 11 is a right side view of the vent shown in FIG. 8.

FIG. 12 is a left side view of the vent shown in FIG. 8.

FIG. 13 is a top view of the vent shown in FIG. 8; and,

FIG. 14 is a bottom view of the vent shown in FIG. 8.

The dash-dot lines represent the boundaries of the design. The dash-dot break lines indicate that no particular length is claimed. The dashed lines in the figures illustrate portions of the design that form no part of the claim.
